UNITED STATES PATENT OFFICE.

ALBERT S. N. OLSON, OF CHICAGO, ILLINOIS.

DESIGN FOR A FIRELESS COOKER.

Application filed February 21, 1922. Serial No. 818. Term of patent 7 years.

To all whom it may concern:

Be it known that I, ALBERT S. N. OLSON, residing at Chicago, county of Cook, and State of Illinois, a citizen of the United States, have invented a new, original, and ornamental Design for Fireless Cookers, of which the following is a specification.

Fig. 1 is a perspective view of a fireless cooker of my design with the door shown closed;

Fig. 2 is a similar view with the door shown open to reveal the internal configuration.

I claim—

The ornamental design for a fireless cooker as shown.

In testimony whereof I hereunto affix my signature.

ALBERT S. N. OLSON.
